(57) **CLAIM**

The ornamental design for a pickup truck luggage rack, as shown and described.

DESCRIPTION

FIG. 1 is a perspective view of a pickup truck luggage rack showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof.

FIG. 9 is an enlarged detail view of area 9 shown in FIG. 1; and,

FIG. 10 is an enlarged detail view of area 10 shown in FIG. 8.

The broken lines in the drawings depict portions of the pickup truck luggage rack that form no part of the claimed design.
